(57) **CLAIM**

The ornamental design for a fitness rack, as shown and described.

DESCRIPTION

FIG. 1 is a front, left, and top perspective view of a fitness rack, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a partially enlarged view of portion 8 taken from FIG. 1.

The dot-dash broken lines are included to show the partially enlarged view only and form no part of the claimed design.

1 Claim, 8 Drawing Sheets
